UNITED STATES PATENT OFFICE.

JOHN W. DOBINSKY, OF HAMILTON, ONTARIO, CANADA.

BOMB.

1,276,736.

Specification of Letters Patent. Patented Aug. 27, 1918.

Application filed September 17, 1917. Serial No. 191,770.

To all whom it may concern:

Be it known that I, JOHN W. DOBINSKY, a subject of the Emperor of Austria, residing at Hamilton, in the Province of Ontario, Canada, have invented certain new and useful Improvements in Bombs, of which the following is a specification.

This invention relates to certain new and useful improvements in bombs.

10 The primary object of the present invention is to provide a bomb that may be either thrown by hand, or discharged by a suitable machine and wherein the bomb containing an explosive is adapted to be set off 15 by contacting with objects at either end thereof.

A further object of the invention is to provide a bomb having a percussion cap at the forward end thereof and with a peculiarly constructed tail whereby an object encountered by said tail will cause the bomb to explode.

With the above general objects in view and others that will appear as the nature 25 of the invention is better understood, the same consists in the novel construction, combination and arrangement of parts herein-after more fully described, illustrated in the accompanying drawings and then 30 claimed.

In the drawings forming a part of this application and in which like designating characters refer to corresponding parts throughout the several views,

35 Figure 1 is a longitudinal sectional view of a bomb constructed in accordance with the present invention, the main body portion thereof partially shown in elevation.

Fig. 2 is an enlarged cross sectional view 40 taken on line II—II of Fig. 1 showing the radial fins carried by the body of the bomb.

Fig. 3 is an edge view of the tail of the bomb and a portion of the bomb body.

Fig. 4 is a cross sectional view taken on 45 line IV—IV of Fig. 1 showing the tail constructed of two parts with the spring retaining plug in operative position.

Fig. 5 is a cross sectional view taken on line V—V of Fig. 1 showing the longitudinal operating rod extending through the tail with the radial arms carried thereby extending outwardly of the side of the tail and

50 Fig. 6 is a cross sectional view taken on line VI—VI of Fig. 1 showing a longitudinal operating rod retained in fixed position.

tion by the fragile transverse retaining member.

Briefly described, the present invention aims to provide a bomb in which the body portion thereof in general respects resembles a bomb of ordinary construction, the same including a movable head at the front end thereof for exploding the bomb upon contact with another object. The bomb carries a tail portion of peculiar construction, the tail carrying a longitudinally movable rod pressed in a direction toward the bomb, but restrained from such movement by a fragile connection. Arms extend radially 65 from the longitudinal rod and project outwardly of the sides of the tail and upon engagement with an object, as in passing the same, the arms will shift the rod and cause the fragile connection to become inoperative whereby the compression means will move the rod toward the bomb and through 70 a cap to explode the contents thereof.

Referring more in detail to the accompanying drawing, the reference numeral 10 designates the body portion of the bomb which may be of any preferred design, and preferably as shown, is of elongated oval shape and is adapted to contain an explosive substance 11 which may include shrapnel, or the parts that constitute the interior filling of a bomb, while openings are provided at each end thereof, the front opening being closed by a fulminating cap 12 while the rear opening is closed by a fulminating cap 13. The outer side of the body portion 10 is provided with readily disposed and rearwardly directed vanes or fins 14 which will assist the bomb in traveling 75 in the direct course in which it is sent.

The forward end of the body portion 10 is provided with a restricted opening 15 spaced from the terminal end thereof and communicating with an enlarged interiorly threaded terminal opening 16 within which 100 is received a closure plug or cap 17 having an opening therein registering with the opening 15 and adapted for the reception of the shank 18 of the spear-shaped exploding head 19, a coil spring 20 surrounding the shank 18 and operatively associated therewith in a manner to hold the same at the limit of its outer movement as shown in Fig. 1, and in a position spaced from the fulminating cap 12. The operation of this 105 form of head is believed to be plainly obvious, it being noted that when the spear

head 19 comes in contact with an object, the same will be moved inwardly against the tension of the spring 20 to engage the fulminating cap 12 in a manner to explode the 5 filling 11 within the bomb.

The tail construction of the bomb includes a pair of plates 21 preferably of the tapered formation shown in Fig. 1 with the inner ends thereof threaded as is illustrated for 10 threaded reception within the opening provided in the rear end of the bomb, while the two side plates forming the body portion of the tail are connected as by screws 22 or similar fastening means shown in 15 Figs. 1 and 4. The longitudinal axis of the tail is provided with a bore 23 communicating with curved oppositely disposed lateral passages 24 and within this longitudinal passage is positioned an operating rod 25 having formed integral therewith radially curved arms 26 projecting through the lateral openings 24 and terminating at a point spaced outwardly of the side edges of the tail. As shown in Figs. 1 and 6 the side 25 plates 21 are formed adjacent the rear end of the bomb 10 with a transverse recess 27, the opposite ends of which are closed by threaded plugs 28, while a fragile cord or similar element 29 extends through said 30 opening 23 and is fixed to the plugs 28, the fragile member 29 being connected to the rod 25 to hold the inner pointed end thereof spaced from the fulminating cap 13. Resilient means is provided for normally holding 35 the rod 25 forwardly projected, and includes a coil spring 30 having one end thereof in engagement with the outer end of the rod 25, while the other end of the spring is engaged by a screw plug 31 threaded into 40 an opening provided in the outer terminal end of the tail 21.

From this description, it is thought that the construction and operation of the tail portion of the bomb is readily apparent, it 45 being noted that should the operating head 19 pass an object and fail to strike the same, it is still possible that the bomb will be exploded by the object coming in contact with one of the radial arms 26 which would shift

the operating rod 25 outwardly of the bomb 50 body 10 against the tension of the spring 30 and thereby direct the fragile member 29, whereupon the spring 30 will assert its force and forcibly move the rod 25 toward the bomb body 10 in a manner to discharge the 55 fulminating cap 13 and subsequently explode the contents of the bomb.

It is to be understood that various changes may be made in the details of construction in this device such as providing additional 60 arms 26 extending from other sides of the tail and while the present form of the invention is what is believed to be the preferable form, it is to be understood that such minor changes may be made without departing 65 from the spirit and scope of the invention as claimed.

What I claim as new is:—

1. A bomb comprising a body portion having an operating head at the front end thereof, a tail carried by the rear end of the bomb and including a pair of plates having their inner ends threaded for reception in the body of the bomb, means for retaining the tail plates in fixed position, said tail having a longitudinal recess and lateral openings communicating therewith, a longitudinal rod provided with radial arms movably positioned in said recess and lateral openings respectively, a transverse fragile 75 element connected with said rod to hold the same fixed, a spring arranged between the outer end of said tail and the outer end of said rod and a plug engaging the outer end of said spring.

2. A bomb comprising a body portion having a discharge head at the front end thereof, a tail carried by the bomb having a longitudinal recess and lateral openings communicating therewith, a rod provided 90 with radial arms movably positioned in said recess and openings respectively, a fragile element operatively associated with said rod for holding the same stationary and means for forcing said rod toward said bomb when 95 said fragile connection is broken.

In testimony whereof I affix my signature.

JOHN W. DOBINSKY.
